(57) **CLAIM**

The ornament design for a stored value card envelope, as shown and described.

DESCRIPTION

FIG. 1 is a perspective view of the stored value card envelope shown in the open position to reveal a stored value card configured for placement inside the stored value card envelope;

FIG. 2 is another perspective view of the stored value card envelope shown with top and bottom flaps in a closed position around the stored value card;

FIG. 3 is another perspective view of the stored value card envelope shown with the top, bottom and left laps in a closed position around the stored value card;

FIG. 4 is another perspective view of the stored value card envelope shown with the top, bottom, left and right flaps in a closed position around the stored value card;

FIG. 5 is front view of the stored value card envelope shown with the top, bottom, left and right flaps in closed position around the stored value card;

FIG. 6 is rear view of the stored value card envelope shown with the top, bottom, left and right flaps in closed position around the stored value card;

FIG. 7 is left side view of the stored value card envelope shown with the top, bottom, left and right flaps in closed position around the stored value card; the right side view being a mirror image thereof;

FIG. 8 is a top view of the stored value card envelope shown with the top, bottom, left and right flaps in a closed position around the stored value card; and,

FIG. 9 is a bottom view of the stored value card envelope shown with the top, bottom, left and right flaps in a closed position around the stored value card.

The dashed lines showing in the figures are included for the purpose of illustrating portions of the stored value card envelope that form no part of the claimed design.
